UNITED STATES PATENT OFFICE.

JOHN A. PRINCE, OF NEW YORK, N. Y.

PAPER-DRYING MACHINE.

SPECIFICATION forming part of Letters Patent No. 633,733, dated September 26, 1899.

Application filed April 27, 1899. Serial No. 714,640. (No model.)

To all whom it may concern

Be it known that I, JOHN A. PRINCE, of New York, (Brooklyn,) county of Kings, and State of New York, have invented new and useful 5 Improvements in Paper-Drying Machines, of which the following is a specification.

This invention relates to a machine for forming the printed, varnished, or painted end of a paper-roll into loops and laying such 10 loops side by side upon a drying-rack. The machine insures a reliable delivery of the supporting-sticks and advances the loops upon the rack by small stages, so that a rapid 15 advance of the loops with a short stroke of the slide is obtained.

In the accompanying drawings, Figure 1 is a side elevation, partly in section, of the machine; Fig. 2, a plan, partly in section, thereof; Fig. 3, a detail side view of part of the 20 rack; Fig. 4, a cross-section through the rack, and Fig. 5 a detail of the gearing $e' f$.

The letter a represents a box adapted for the reception of a battery of superposed sticks or slats b , which may be discharged singly 25 through the lower slotted end of the box.

$c c$ are a pair of parallel feed-chains, the upper run of which is inclined from the bottom upward. The chains c describe a triangular course, running over sprocket-wheels 30 c^2 and idlers $c' c^3$, of which the wheels c' are placed below box a , while the wheels c^2 are placed directly in front of a pair of parallel rails d .

To each of the chains c are secured two 35 (more or less) pairs of noses c^4 , which by the movement of the chains traverse the lower open end of box a to engage the lowermost stick b and deliver it upon the ends of the rails d , which are supported by hangers d' .

Motion is imparted to the chains c from a 40 counter-shaft e , having toothed wheels e' , which engage smaller toothed wheels f , fast on stub-shafts f' , carrying the sprocket-wheels c^2 , Fig. 5. One of these stub-shafts is driven 45 by belt g' from power-shaft g . Step-pulleys $g^2 f^2$ on the shafts $g f'$, respectively, permit the chains c to be driven faster or slower, so that the machine may be set for lighter or heavier paper.

The slides for feeding the sticks intermittently along the rails d are constructed as follows: To the inner sides of the hangers d'

are secured rolls d^2 , upon which are supported the reciprocating slide-bars h . These bars are connected at intervals by rods h' , to 55 which are attached the longitudinal bars or rails h^2 , to which in turn the pawls h^3 are pivoted, one row of pawls being arranged vertically above each of the rails d . Reciprocating motion is imparted to the slide from 60 wheels e' by wrist-pins e^2 , pitmen i , and shaft i' , turning in bearings h^4 of bars h .

The forward slide, constructed as described, drives a similarly-constructed rear slide, the stroke of which is about one-half that of the 65 forward slide and the pawls j of which are correspondingly set closer together. The rear slide receives motion from one of the rods h' of the forward slide by link k , lever k' , fulcrumed at k^2 , and link k^3 , that engages one of 70 the rods j' of the rear slide. The object of the two slides is that the rear loops of the paper, which are already partly dried, be suspended more closely together than the front wet loops.

The gearing $f' e'$ of the chains and the slides should be so proportioned that the slides complete two or more strokes between the delivery of one stick and the delivery of the next stick. Thus in the drawings the slides 80 will reciprocate four times for each complete rotation of the chains, so that while two sticks are delivered the slides will make four strokes. The consequence of this arrangement is that the slides will not advance a 85 loop of paper for the whole width of such loop during each stroke, but only for, say, half the width, so that the loops will advance in small stages and be more thoroughly dried while traveling.

The operation is as follows: A stick b will be deposited upon ends of rails d , and the first loop of paper A delivered from roller A' will be laid around it. The stick will now be engaged by pawl 1 and advanced for 95 one-half the space desired. During the next stroke pawl 1 will run idle and the stick will be engaged by pawl 2 and advanced for another half-space. At the completion of this second stroke a new stick will be delivered to 100 pawl 1, so that pawls 1 3 5, &c., will alternate in being active and idle with pawls 2 4 6, &c. The consequence is that while the stroke of the machine is small the paper will be moved

along rapidly in small stages to be effectively dried.

What I claim is—

A paper-drying machine composed of a pair 5 of inclined driving-chains having noses, a stick-box, a pair of rails upon which the sticks are deposited by the noses, a pair of slides having pawls adapted to engage the

sticks, and means for driving the chains and slides at different speeds, so that alternate 10 pawls will run alternately idle, substantially as specified.

JOHN A. PRINCE.
